UNITED STATES PATENT OFFICE.

WILLIAM E. BENSON, OF KANSAS CITY, MISSOURI.

BULLETIN-BOARD.

SPECIFICATION forming part of Letters Patent No. 603,248, dated May 3, 1898.

Application filed January 24, 1896. Serial No. 576,696. (No model.)

To all whom it may concern:

Be it known that I, WILLIAM E. BENSON, a citizen of the United States, residing at Kansas City, in the county of Jackson and State of Missouri, have invented certain new and useful Improvements in Bulletin-Boards; and I do hereby declare the following to be a full, clear, and exact description of the invention, such as will enable others skilled in the art to 5 which it appertains to make and use the same.

My invention relates to a bulletin-board especially designed for use of lodges, clubs, churches, societies, and any organization having a list of members, also for directories for 10 buildings, telephone-lists, and for other purposes; and the object that I have in view is to provide a simple and inexpensive construction by which an alphabetical and numerical register is combined in such a way that it will 15 indicate at any and all times an alphabetical list of members, as well as the numerical strength of the organization or the like, and also to provide for the convenient changing of the list of the members according as the 20 number is increased or diminished.

With these ends in view and such other ends as pertain to a device of this character my invention consists of a bulletin-board provided with vertical parallel guide-strips 25 adapted to contain columns of numbers in consecutive order, combined with one or more 30 slidable cases or frames fitted between and within guide-strips and constructed to contain removable name-slips which are adapted 35 to be brought opposite to the numbers in the columns on the guide-strips, and suitable means for holding the slidable cases or frames within the bulletin-board; and the invention further consists in the construction, combination, and arrangement of parts, which will 40 be hereinafter fully described and claimed.

To enable others to understand my invention, I have illustrated the preferred embodiment thereof in the accompanying drawings, 45 forming a part of this specification, and in which—

Figure 1 is a front elevation of my improved bulletin-board, showing one of the movable slip-carrying cases partially withdrawn from 50 the board. Fig. 2 is an end view looking at the lower end edge of the bulletin-board. Fig. 3 is an enlarged horizontal sectional view through a portion of the bulletin-board to

illustrate the detailed construction thereof. Fig. 4 is a side elevation of the bulletin-board. 55

Like letters of reference denote corresponding parts in all the figures of the drawings, referring to which—

A designates the bulletin-board or back board proper, which has its exposed face divided into spaces for the name of the organization, as at a, and into three vertical spaces for the reception of a corresponding number of vertically-slidable slip-containing cases B C D, although the number of spaces for the 60 slip-containing cases may be increased or diminished according to the numerical strength of the organization, &c. This board is surrounded by molding-strips b, and the vertical spaces for the slip-carrying cases are formed 65 by and between the vertical guide-strips c c c, which are parallel to each other and spaced far enough apart to accommodate between themselves the slip-carrying cases. To these vertical guide-strips c are fastened the numbered strips or plates d d, which are wide 70 enough to extend beyond the guide-strips c, as shown by Fig. 3, and on the exposed faces of these numbered strips or plates are stenciled or otherwise inscribed the columns of 75 numbers, as shown.

The first plate or strip d to the left is shown by Fig. 1 as having a column of figures from "1" to "25," inclusive. The second strip or plate d contains another column of figures, 80 numbered from "26" to "50," inclusive, and so on throughout the width of the bulletin-board; but this arrangement and numbering is arbitrary and may be varied at pleasure.

The slip-carrying cases or frames B C D 85 are so proportioned as to fit snugly between the guide-strips c and under the number strips or plates d, so that the slidable frames or cases are held and confined in place between said strips and the back board, while 90 the front sides of such cases or frames are open and exposed to view. I prefer to make these slidable frames or cases of sheet metal with turned-over or flanged edges, as shown by Fig. 3; but the material used and the detailed construction of the frames or cases 95 may be varied within wide limits and without departing from the spirit of my invention. Each frame is adapted to slide vertically between and within the strips c d, and 100 ready access to the case or frame can be had.

by withdrawing the case from the lower or upper open side of the bulletin-board. To hold the slip-case in position, I prefer to use a suitable form of spring-catch, (indicated at 5 E as having a suitable finger-piece or handle;) but the construction of this catch forms no part of my present invention, and any suitable form of catch may be adopted and used.

The names of the members, with or without 10 their addresses, are inserted on slips or cards (indicated at F in the drawings) which are fitted or sprung within the flanged cases or frames, so as to be held in place therein. Each card or slip F is so proportioned and 15 arranged as to occupy a position at one side of and in line with the numerals on the strips d, and the number of slips or cards in one frame or ease corresponds to the numbers on the strip d next to or over the frame or ease, 20 so that the total number of members of the organization can be easily ascertained by a glance at the bulletin-board. For convenience the names of the members are arranged in alphabetical order, and thus the total number 25 of names and the name and address of any individual member can readily be ascertained by consulting the bulletin-board. As the name of each member is inscribed on an individual card, the cards can easily be 30 changed or adjusted in the several cases or frames according to changes in the membership of the organization.

To protect the name-slips from dust and dirt, as well as to prevent tampering with the 35 cards or slips, I have provided a protective glass front consisting of panes of glass G, which are fitted against the numbered strips d and are held or confined in place by means of the molding-strips H, which are secured 40 to the strips d by means of glue or by screws that pass between the edges of the glass panes G, and thus serve to clamp the glass panes securely in position. The vertical molding-strips H are joined at top and bottom 45 to the horizontal moldings I, and these moldings serve to impart a finish to the exposed front of the bulletin-board.

The bulletin-board may be ornamented or finished in any approved style, and it may 50 have the eyes J or other devices for suspending it on a wall.

It is thought that the mode of using and the advantages of my bulletin-board will be readily understood and appreciated from the 55 foregoing description, taken in connection with the drawings.

I am aware that changes and alterations in the form and proportion of parts and in the details of construction of the devices herein 60 shown and described as the preferred embodiment of my invention may be made by a skilled mechanic without departing from the spirit or sacrificing the advantages of my invention, and I therefore reserve the right to 65 make such modifications as fairly fall within the scope of my invention.

While I have described the bulletin-board

as provided with vertically-slidable slip-carrying cases guided between guide-strips as the preferred construction, yet I am aware 70 that the slip-carrying case can be made stationary within the bulletin-board and provided with a hinged glass door.

Having thus fully described my invention, what I claim as new, and desire to secure by 75 Letters Patent, is—

1. The bulletin-board herein shown and described comprising the stationary frame having a closed back, parallel guide-strips c fixed to said back and within the frame, number-plates attached to the guide-strips and inscribed with columns of figures in consecutive order, glass front or fronts fastened to said stationary frame and the guide-strips by suitable devices, a series of vertically-slidable 85 cases confined edgewise between the guide-strips and laterally between the back and number plates, and name-slips removably fitted in said cases, a series of such name-slips being provided for each ease and each slip ar- 90 ranged in alinement with one figure in a column on one number-plate, all arranged and combined for service as set forth.

2. A bulletin-board comprising a back, a series of guide-strips attached thereto, a series of number-plates of greater width than the guide-strips and fastened to the latter to project beyond the edges thereof and serving, in connection with the back, to confine the sliding cases against lateral displacement, 100 and the glass-front panes fastened to the number-plates, combined with a series of slid-able cases fitted edgewise between the guide-strips and laterally between the back and the projecting edges of the number-plates, and 105 name slips or cards fitted in the slid-able cases, substantially as described.

3. A bulletin-board comprising a back, a series of guide-strips attached thereto, a series of number-plates of greater width than 110 the guide-strips and projecting, at their edges, beyond the same to serve in connection with the back as guides to confine slid-able cases against lateral displacement, the glass-front panes arranged over the number-plates, the 115 molding-strips applied over the edges of the glass-front panes, and the fasteners passed between the edges of the glass-front panes and holding the moldings, the glass panes, and the number-plates on the back, combined 120 with a series of slid-able cases fitted edgewise between the guide-strips and laterally be- 125 tween the back and the projecting edges of the number-plates, means for locking said cases in a detachable vertical position, and removable cards or slips carried by the slid-able cases, substantially as described.

In testimony whereof I affix my signature in presence of two witnesses.

WILLIAM E. BENSON.
